UNITED STATES PATENT OFFICE.

LÉON HATOT, OF PARIS, FRANCE.

ELECTROMAGNETIC CLOCK.

Application filed March 11, 1925, Serial No. 14,802, and in France March 21, 1924.

The present invention refers to clocks the pendulums of which have their oscillations maintained by periodical electromagnetic impulses of the known type wherein a part 5 lifted at each oscillation by the ratchet wheel controlling the hands acts as a switch by coming into contact with a contact spring. The devices which are the object of present invention, are combined in order to reduce the amount of mechanical power necessary for controlling the hands and the switch and to allow a very precise and easy regulation of the several elements which have to be considered in the working (chiefly of the point in the path of the pendulum where driving catch is to begin actuating ratchet wheel). Thereby, as explained hereinbelow, isochronism of oscillations can be obtained.

10 The invention has also for an object improvements in the shapes to be given to certain parts of the clock in order to reduce the cost price and to allow an easy moving of the clock.

15 The invention has for a further object novel shapes and proportions for parts of a clock set up according to invention and provided with a comparatively short and light pendulum. Such a clock is shown, by way 20 of example, on appended drawings at a scale, value of which will be given hereinafter.

On appended drawings:

Figs. 1^a, 1^b and 1^c show controlling parts of switch and switch itself as they used to be made, whereby some of the improvements which are set forth hereinbelow may be described in a more precise manner. Said parts and switch are drawn on a scale of 1/1 according to centimeter scale shown in 25 E on Fig. 1^a.

Fig. 2 shows at the same scale the whole clock mechanism in front view, wherefrom the dial and its supporting plate are supposed to have been taken away.

Fig. 3 is a vertical section passing through shafts bearing hands.

Fig. 4 is a view of supporting plate behind dial together with the several parts which are mounted on said plate.

50 Figs. 5^a, 5^b, 5^c and 5^d show on an enlarged scale an improved form of execution of the contact springs.

Figs. 6^a, 6^b and 6^c show on an enlarged scale another form of execution of the contact springs.

Fig. 7 is a partially sectional detail view at a scale of 5/1 of the ratchet wheel, catch and switch.

Fig. 8 is a section along line x—y of parts shown on preceding figure.

On appended drawings Fig. 1^a shows on the scale 1/1 the known parts which usually go to build up an electromagnetic clock of the type which is considered.

The spring 1 bears a part 2 which after 65 each stroke of the pendulum comes between two teeth of the ratchet wheel 4 from where it is lifted each time the driving catch 3 makes a tooth of the ratchet wheel advance.

Part 2 is mounted on the end of spring 1 70 and has the shape shown on an enlarged scale on Fig. 1^b.

In order to ensure a correct working, part 2 must always be brought back, after each advance of the ratchet wheel, to the position 75 in which it is shown on Fig. 1^c. To arrive at this result with certainty, practice shows it is necessary to bind spring 1 strongly enough to oblige part 2 to bear against ratchet wheel with a comparatively high pressure 80 exerted in the direction of arrow f₁. The reason of this is the inertia of wheel causes it to advance more than by the interval between two teeth: The edge R of part 2 bears on the inclined rear part MN of ratchet 85 tooth and has a tendency to bring the wheel back; this backward movement is accompanied by a comparatively important slipping movement: In order to make sure this will happen in spite of the unevennesses 90 on back part MN of the tooth, it is necessary to provide for a comparatively important force acting in the direction f₁. The work of this force, when ratchet advances, is a loss of mechanical power and so is the 95 work of the frictional forces between the slipping surfaces. Practice shows further that to provide for a good working and to prevent the making and regulation of the parts from being too difficult, the pitch of 100 the ratchet toothwork should be comparatively great (above 2 millimeters). This makes the frictional losses still greater, as the tip N of the tooth moves at each oscillation, a distance equal to width of a tooth, 105 whilst slipping on part 2.

Fig. 1^c shows a form of execution of switch. Spring 1 bears a pin 6 made out of a precious metal and adapted to come into contact with two parts 7 and 8 also of 110

precious metal. These parts are U-shaped and are riveted on two corresponding contact spring strips 9. In practice only one arm of each part 7 and 8 bears on pin 6. 5 This construction obliges a comparatively great quantity of precious metal to be used whilst only a very small part thereof is really used for the electric contact itself.

Above described devices have been recalled 10 to mind in order to show exactly what improvements have been brought thereto, said improvements being described hereinbelow.

Figs. 2, 3 and 4 show how the several parts of a clock mechanism are put together 15 according to present invention.

The pendulum bears at its lower part a magnet 10 controlled by a stationary electromagnet 11. All parts of mechanism are mounted on plate 12 placed behind the dial 20 13 of clock.

The gear system controlling the hands is shown at A. The spindle 14 of ratchet-wheel and the spindles of the gear wheels pivot on plates 15^a and 15^b on which also, 25 pivots spindle 16 of regulating catch of ratchet. Said catch bears an arm 17 provided with a pin 18 coming into contact, at each actuating stroke of pendulum with contact springs 19 and 20.

30 These contact springs and their support are shown in perspective on an enlarged scale on Fig. 5^a. Springs 19 and 20 are cut out of a thin strip of steel so as to appear as shown on Fig. 5^a. They are 35 superposed as shown on said figure so as to provide two very narrow strips brought close one to another and adapted to come into contact with contact pin 18.

The ends of the springs are twisted and 40 brought in a plane perpendicular to that of springs themselves as clearly shown on perspective view 5^a. On the other hand small cappings 21 of precious metal are placed on said ends of springs. Each capping consists in a small and very thin plate folded up as shown on perspective views (Figs. 5^b and 5^c). Mounting of springs is shown on Fig. 5^a. Springs 19 and 20 are secured on square-shaped support S by means of 45 screws V. These provide also for holding plates P₁ and P₂. Through plate P, passes regulating screw 22 bearing on plate 23. Latter plate is less flexible than springs 19 and 20 which are brought to bear against 55 end of same. Regulating screw 22 allows control of position of plate 23 on which, as stated, ends of springs bear.

Instead of two contact strips, four can be used. In view of this, spring 24 is 60 superposed to springs 19 and 20 as shown in perspective on enlarged scale on Fig. 6^a. This spring 24 is cut out so as to form two strips. The ends of these are twisted and curved as shown on Fig. 6^a and small cappings similar to capping 21 are secured on

same. Springs 19-20 and 24 are superposed as shown on Fig. 6^b. The small cappings are placed very close one to another and are perpendicular to pin 18; thereby weight of precious metal necessary for making this pin 18 borne by contact arm 17 can be considerably reduced. For instance, it can be sufficient to use a small portion of a tube 25 of precious metal which is set round part of pin 18 coming into contact with 75 springs.

Such forms of execution show over that drawn on Fig. 1^c, the obvious advantage to require a considerably smaller quantity of precious metal, the device working nevertheless under conditions absolutely as good. 80

Figs. 7 and 8 show on a scale 5 times larger than centimeter scale in E, the ratchet, catch and switch device.

The driving catch is suspended by means 85 of a flexible strip 26 top of which is clamped in stationary holder 27 borne by pendulum whilst lower end is clamped between parts 28 and 29. On part 30 secured to latter parts driving catch 31 is pivotally mounted. The 90 regulating screw 32 allows the pivoting spindle 33 of the driving catch to move in direction of arrow f₂ away from the pendulum. The screw 34 allows a regulation of depth of engagement of driving catch with 95 the teeth of the ratchet-wheel 35 by raising more or less the end of the catch in the direction of arrow f₃.

The ratchet-wheel 35 is cut as shown on 100 Fig. 7 and shows semi-circular intervals between teeth. The regulating catch 36 is secured to spindle 16 and is provided with arm 17 bearing in its turn the contact pin 18. The electric current arrives through the spiral spring 37 secured by one end to projection 38 of arm 36 and by the other to split collar 39 fitted with some friction on projection 40 cast with casing. 105

The end of regulating catch 36 shows two surfaces AB and BC forming together a 110 slightly obtuse angle (see Fig. 7^a). One of these surfaces AB is nearly parallel to the line x-y going from spindle 14 of ratchet wheel 35 to spindle 16 of the regulating catch. Said surface bears on tip of tooth d₁ which is situated close to and directly above line x-y. The regulating catch 36 has therefore a tendency, by reason of its weight and of the action of spiral spring 37, to force the ratchet wheel back through 115 its action on the tooth d₁. The tip of next tooth d₂ comes then against end C of surface BC so that device stops in a predetermined position. The following tooth d₃ is then placed in the path of the end of driving catch 31. 120

The momentum of inertia of regulating catch 36 and of its arm 17 is comparatively important. The total weight of these parts should be above $\frac{1}{2}$ gramme. On the other 125 130

hand a rotation is imparted to the collar 39 which is sufficient to make the force which brings surface AB of the catch against the tooth d_1 big enough to drive the ratchet 5 wheel back until it is stopped by contact between tooth d_2 and tip C of catch.

Lastly, by means of the screw 34, the depth of engagement of the driving catch 31 is regulated so as to force said catch to 10 rotate tooth d_3 and to disengage it when the ratchet-wheel has advanced exactly the quantity corresponding to pitch of its tooth-work.

The devices work in the following manner:

When the driving catch 31 comes into contact with the tooth d_3 , the tooth d_1 raises the regulating catch 36 and causes it to turn in the direction of arrow f_5 . The speed of 20 this rotation grows when speed of pendulum becomes greater. The pin 18 is thus caused to come into contact with the contact springs 19 and 20 and the kinetic energy contained in the regulating catch serves to raise these 25 springs. As soon as the ratchet-wheel has advanced the value of one tooth interval, the regulating catch falls back and if ratchet-wheel has advanced somewhat to much, the surface AB presses on tooth d_1 , whereby 30 ratchet wheel is brought back in its correct position.

It should be noted that the necessary amount of energy for this object is much smaller than with device shown on Fig. 1^b. 35 The reason of this fact is the working force acts on a lever arm value of which is very near the radius of ratchet wheel and therefore near its maximum value. Moreover there is hardly any slipping whilst the return movement is being made, as the tooth d_1 is nearly on the line joining the spindles of ratchet-wheel and regulating catch. If surface AB is well polished and slightly lubricated, it will be a sufficient reason for 40 avoiding jamming and allowing return movement to be made with a very small expenditure of energy. Lastly the device is easy to make and the working is most reliable, even with a very small pitch of the 45 tooth work. Therefore a very small ratchet wheel can be used and the distance between supporting part 26 and driving catch 31 can be made very small. Thus all friction is greatly diminished and, as is well known, 50 friction is the principal cause for irregular working of clocks.

Nearly all the loss of energy is caused by the impulse given to the regulating catch. 55 This loss is approximately proportional to 60 the square of the amplitude of the oscillations and it thus affords means for ensuring stability of operation and regularity of working. By means of regulating screw 32 it is possible to determine at will the moment 65 during stroke of pendulum when the drive

of the driving catch is to begin and thereby the moment when the retarding percussion begins. The motive power is put into action during a time which can be regulated by means of contact screw 22. As is well known, by providing for the retarding and driving impulses at the proper moment with reference to the dead point, the oscillations can be caused to remain isochronous even if the amplitude were to vary slightly with 70 reference to the amplitude corresponding to accurate time-keeping and to a constant voltage of the battery. Thus if said voltage and thereby the amplitude of the oscillations were to vary, this would have no effect 75 on the period of oscillation and on the accuracy of the time-keeping.

The described devices allow this result to be easily achieved; all the elements which influence the operation are very easily regulated with a very great precision. A greatly improved regularity can be thus obtained, the pendulum used being nevertheless comparatively very light and very short.

Figs. 2, 3, 4, 3^a and 3^b show a preferred 90 form of execution of the casing and other parts of clock mechanism.

All the parts are fixed on a foundation plate 12 over which is placed the dial 13 of the clock. The rod of pendulum is made 95 out of a strip of "invar" metal 41 in one or more parts the top of which forms a socket borne by the suspending device.

The battery 42 is secured on a plate 43 attached to the foundation plate by means of 100 projections 44. The terminals of the battery are connected, one with the contact spring 19 through the wire 59 and the other with the contact arm 17 through the wire 60, the stationary coil 11, and the spring 37.

The electromagnet 11 is secured to plate 43^a. The dial and the hands a_1 , a_2 , a_3 are protected by a glass 49 held between the two parts 50 and 51 which are made out of two 110 brass sheets stamped and soldered one on the other. These parts form an opening rim for the glass which is provided with hinge 52 mounted on part 50 on one side and on foundation plate on the other by means of screws 53 and 54 (see section on enlarged 115 scale on Fig. 3^a).

The movable parts are fixed in clock casing by means of threaded rods such as 55 and stamped ring 57. A cover 56 which can be set on casing with some friction shuts rear opening of the clock after battery has been introduced in same.

The above described system of securing devices allows an easy setting of an electrical control device in the casing of an ordinary spring clock without requiring any change thereto. They are much easier and cheaper to make than the usual hinged rims with bevelled glass.

The pendulum can be immobilized for 130

- transport by means of a screw passing through rod 41 of pendulum into a projection cast with casing. The rod of pendulum can also comprise a part 41_a and a part 41_b 5 former of which holds the magnet, as shown on Figs. 3 and 3^b. This construction allows the removal of the heavier part of the pendulum for transport and the easy hooking on of same when clock is set up again.
- 10 The devices shown on Figs. 5 and 6 are conveniently used as an auxiliary switch actuated by the pendulum. It is sufficient for this to secure such a device in 0 as shown on Fig. 4 so as to cause a pin to raise the contact 15 springs at each oscillation.

The working of the ratchet wheel and of the catch as described hereinabove can be used for the electric maintenance of any oscillating device and chiefly for that of an 20 equilibrated pendulum cooperating with a spiral spring. In latter case, the above described devices are more particularly useful, inasmuch as they reduce the friction which may arise, which is very important when the 25 momentum of inertia of the pendulum is small.

What I claim is:

1. In a ratchet escapement comprising a driving catch secured to the clock pendulum, 30 a ratchet wheel controlled by the driving catch, and a regulating catch engaging the ratchet wheel, a spindle on which the regulating catch is pivotally mounted, the regulating catch extending substantially parallel 35 to the line connecting the spindle with the

center of the ratchet wheel and ending with a plane surface making an obtuse angle with the said line whereby this surface engages the interval between two teeth of the ratchet wheel disposed near the abovementioned line, and means whereby the regulating catch brings back the ratchet wheel to the position corresponding to an advance equal to the interval between two teeth.

2. A ratchet escapement for electromagnetic clocks as claimed in claim 1 comprising a contact pin borne by the regulating catch, disposed in the electric circuit controlling the clock, a stationary contact spring cooperating therewith, two stationary 45 plates between which the spindle of the regulating catch is mounted, a lateral arm borne by said regulating catch and bearing the contact pin, a spiral spring secured to said lateral arm, a socket secured to the spiral spring and a stationary pin on which said socket is frictionally set and round which it is rotatable.

3. A ratchet escapement for electromagnetic clocks as claimed in claim 1 comprising a slightly yielding part mounted on the pendulum and on which the driving catch is pivotally mounted, a regulating screw passing through the yielding part and bearing against the pendulum, and a second regulating screw passing through the yielding part and bearing against the driving catch.

In testimony whereof I have signed my name to this specification.

LÉON HATOT.
